(No Model.)

T. H. SYMINGTON.
OILER FOR RAILWAY AXLE BEARINGS.

No. 414,783.

Patented Nov. 12, 1889.

UNITED STATES PATENT OFFICE.

THOMAS H. SYMINGTON, OF BALTIMORE, MARYLAND.

OILER FOR RAILWAY-AXLE BEARINGS.

SPECIFICATION forming part of Letters Patent No. 414,783, dated November 12, 1889.

Application filed June 14, 1889. Serial No. 314,813. (No model.)

To all whom it may concern:

Be it known that I, THOMAS H. SYMINGTON, a citizen of the United States, and a resident of the city of Baltimore, and State of Maryland, 5 have invented a new and useful Improvement in Oilers for Axle-Bearings for Railroad-Cars or Locomotives, of which the following is a complete specification.

Figure 1 is a longitudinal sectional elevation of a car-axle box, showing the oiler in the bottom thereof. Fig. 2 is a plan view of the oiler when removed from the axle-box.

In the drawings, A represents the end of an axle; B, a box inclosing the end of the 15 axle; C, the bearing-block resting upon the axle and bearing against the inner side of the top of the axle-box.

D is the oiler-box, perforated by apertures d d d d at the sides and ends for the admission of oil which lies in the bottom of the 20 axle-box.

E is a cover to the oiler-box D, perforated in its top by the small holes e e e, distributed over its surface, and having the large circular 25 opening G in its center. The cover E is bolted to the box D by means of bolts e² passing through them. In the center of the box is cast a ring d². This ring may be perforated laterally with holes for the exit and inflow of 30 oil, or it may be slotted, as shown in Fig. 2, with slots d³. The size of the slots will depend upon the amount of oil which it is desired to throw upon the axle.

F is a cap of a size to fit in the opening G 35 in the cover E, and provided upon its interior at the center with a circular lug f². This lug may be of any desired shape; but I prefer to make it circular. The lug f² is made of such a size as to fit snugly into the ring d² 40 and in operation acts as a plunger working in a cylinder, the ring d² forming the cylinder.

f³ is a helical spring surrounding the cylinder d² and supporting the cap F in such a 45 position that the plunger f² will be raised a desired distance, which is approximately one-half of the height of the cylinder above the bottom of the cylinder. The piston or lug f² is perforated by the holes f⁴, f⁵, f⁶, and f⁷ in 50 a line with one another, which line is parallel to the axis of the axle.

My invention particularly relates to the

shape and position of the holes and the effect produced thereby. The holes are constructed as follows:

The hole f⁴ is vertical while passing through the plunger f², but inclined toward the end of the axle while passing through the top of the cap F. The inclination of this hole must be carefully determined in every case in 60 which the oiler is to be employed, in order that the oil forced from it by the motion of the cap F will be thrown far enough and yet not too far upon the bearing-surface of the axle.

The hole f⁷ is identical in shape with f⁴, except that it is inclined in an opposite direction, so as to throw oil toward the inner 65 end of the bearing-surface of the axle.

The holes f⁵ and f⁶ are two branches of a 70 central hole f⁸, and are inclined away from the axial line of said hole, but in a line parallel to the axle. The inclination of these holes is such as to distribute the oil ejected from them upon the surface of the axle midway between the points at which the oil ejected from hole f⁴ and f⁷ strike it. The vertical hole f⁸ is made of smaller diameter than the hole f⁴ and f⁷, for the reason that, being in the center of the piston or plunger, 75 the pressure of oil upon it is greater than upon the holes f⁴ and f⁷, and too much oil will be forced through it unless it is made smaller than the others, notwithstanding the fact that it divides into two parts before it 80 leaves the cap.

For the effective operation of my device it is necessary that the holes f⁴, f⁵, f⁶, and f⁷ should be maintained in a line parallel to the axle. For this purpose, where a circular cap 90 is employed, the lugs f⁹ f⁹ are cast upon the sides of the cap, and a guide or guides f¹⁰ f¹⁰ are cast upon the interior of the oiler-box D, between which the lug f⁹ rests and prevents the cap from turning. This same result might 95 be accomplished by making the cap of any form other than circular or casting a fin upon it which would enter a notch in the cover E. The lugs f⁹, being on the lower edge of the cap F, serve to prevent the cap from being 100 thrown out of the device by an unusual expansion of the spring.

I am aware that a device somewhat similar to mine was patented by William Painter in

1871; but my invention differs very materially from his in accomplishing a result of which his is incapable.

The operation of the device is as follows:
5 The oiler, secured together as a compact whole by the bolts e^2 e^3 , is placed in an axle-box beneath the axle. Oil is then poured into the box to a sufficient depth to about half submerge the oiler. When the car or locomotive upon which the device is employed is set in motion, the heavy cap F, sustained by a light elastic spring f^3 , will reciprocate up and down with the jolting of the axle-box. This will cause the plunger f^2 to be forced
15 into and withdrawn from the cylinder or ring d^2 and the oil contained in said cylinder to be forced through the holes f^4 , f^5 , f^6 , and f^7 in a line parallel to the axle upon the surface, thereby distributing upon it fresh oil with
20 every jolt of the truck.

Having thus described my invention, what I claim, and desire to secure by Letters Patent, is—

1. In an axle-oiler, the combination of a
25 cylinder containing oil with a plunger reciprocating therein by the jolting motion of the vehicle, said plunger being sustained by a flexible spring and being perforated with two or more holes in line with the axis of the axle

and inclined, respectively, toward the front 30 and rear end of the bearing-surface of the axle, substantially as described.

2. In an axle-oiler, the combination of a cylinder containing oil, said cylinder being perforated transversely to permit the escape 35 of superfluous oil, with a plunger reciprocating therein by the jolting motion of the vehicle, said plunger being sustained by a flexible spring and being perforated with two or more holes in line with the axis of the axle 40 and inclined, respectively, toward the front and rear end of the bearing-surface of the axle.

3. In an axle-oiler, the combination of the cylinder containing oil with a plunger reciprocating therein by the jolting motion of the vehicle, said plunger being sustained by a flexible spring and being perforated with two or more holes in line with the axis of the axle 45 and inclined, respectively, toward the front and rear end of the bearing-surface of the axle, and means for preventing the rotation of the plunger and maintaining the parallel between the line of holes and the axle.

THOMAS H. SYMINGTON.
